UNITED STATES PATENT OFFICE

CYRUS W. SALADEE, OF TORRINGTON, CONNECTICUT.

TWO-WHEELED VEHICLE.

SPECIFICATION forming part of Letters Patent No. 298,414, dated May 13, 1884.

Application filed July 5, 1883. (No model.)

To all whom it may concern:

Be it known that I, CYRUS W. SALADEE, a citizen of the United States, and a resident of Torrington, in the county of Litchfield and 5 State of Connecticut, have invented certain new and useful Improvements in Two-Wheeled Vehicles, of which the following is a specification.

My invention relates to two-wheeled vehicles; and it consists in certain details of construction, fully described hereinafter.

In the drawings, Figure 1 is a side elevation of a complete "side-bar road-cart" embodying my invention. Fig. 2 is a half-plan view of the 15 same with the wheels, body, and shafts removed. Figs. 3 and 4 are detached views of the parts composing one form of the "adjusting device," which is interposed between the shafts and the front end of the frame. Figs. 5, 6, 7, 8, 9, and 20 10 represent modifications.

Referring to Figs. 1, 2, 3, and 4, I is the axle—in this instance it is a crank-axle to admit of hanging the body low down. To this axle is secured a platform-frame of suitable 25 construction.

As shown, D are the side bars of the frame, rigidly secured to the axle.

E is the front cross-bar, and E' the rear.

F F' are cross-springs of any kind connecting the side bars and supporting the body.

F', as in dotted lines, Fig. 2, represents semi-elliptic side springs, which may be substituted for the cross-springs F, and are extended from the front to the rear cross-bars, directly under 35 the body, at the sides.

B represents the shafts forming part of the shaft or pole frame, and extended rearward and pivotally connected to the axle or other part of the platform-frame by the shackle L.

40 C is a flexion-spring, secured to the under side of the shafts at their rear ends, and inclosed by a clip, P', adapted to be moved on the shaft forward or back to regulate the tension of the spring C. The main plate of the 45 spring C extends back of the rear end of the shaft, and forms an eye, whereby to connect the shaft to the shackle-bearing L. The front end of the main plate of the spring C extends forward and pivotally connects at J with an 50 adjustable connection, as a vertical screw-bolt, K, the lower end of which passes through the

plate N on the cross-bar E. "Set-nuts" m and o—one above and one below the plate N—firmly hold the bolt at any desired point to which it is set. When desired, the plate N may be 55 made in two pieces, with a joint, N², interposed between the vertical bolt and cross-bar E, as shown in Fig. 10, whereby to admit of the free movement of the spring C when the latter is of a form to render this play desirable. As the rear end of the shaft-frame is pivotally connected to the axle or frame supported thereby, and as there is an elastic connection between the front end of the frame and shaft-frame, any up or down movement of the 60 shafts from the motion of the horse is taken up by the elastic connection of the spring C, and thereby prevents a transmission of the motion to the body. By means of the adjusting device K the shafts may be "set" up or 65 down, according as the horse is high or low. The arrangement of the side bars and cross-bars connecting them constitutes a frame in which longitudinally-arranged semi-elliptic springs may be used, as well as cross-springs. 70 75

The combination here shown of side bars secured upon the axle, the latter being dropped down between the side bars, as before described, and cross-bars connecting the latter, front and back, produces a two-wheeled running-gear in which may be used any of the 80 well-known kinds of cross or longitudinally-arranged springs, and hence I am not limited to any special arrangement of body-supporting springs.

For the purpose of maintaining the square of the frame, stays H are extended from the axle to the side bars, as shown in Fig. 2.

Fig. 5 represents a modification. The side bars of the platform-frame are pivotally connected to the axle, and the rear ends of the shafts are rigidly secured to the axle.

Fig. 6 is a side elevation, and Fig. 7 is a plan view, of a modification wherein the shaft-frame is pivotally connected to the cross-bar E, and the shafts are connected at the ends with springs C', rigidly secured to the axle. These springs serve the same purpose as spring C in Fig. 1.

The arrangement of the spring C and shafts B, pivotally connected to the axle, is applicable in other styles of this class of carriage—100 as, for example, in that class of "road-carts"

in which the body is mounted upon the axle on two side springs of elliptical or semi-elliptical form. If preferred, a flexion cross-spring may be substituted for the longitudinal springs C.

In Figs. 8 and 9 are illustrated a suitable arrangement and combination of springs for a phæton or drop-front body. In this modification I use a straight axle, (since the elevated rear portion of the body cannot come in contact with it,) and for the rear cross-spring, F, I substitute a suitable spring-support mounted upon the rear end of the platform-frame, preferably an elliptic spring, F', or two elliptic springs longitudinally arranged, one on each side of the frame, to support the rear end of the body, may be used. The drop-front of the body is supported upon the cross-spring F, the same as in Fig. 1, or by flexion-springs having their heavy ends secured to the under side of the bars D, or otherwise.

I claim—

1. In a two-wheeled vehicle, the combination of the axle, platform-frame connected therewith and supporting the springs, body supported by said springs, and shaft or pole frame pivoted to the axle, and spring longitudinally interposed between the shaft-frame and platform-frame, substantially as set forth.

2. The combination, with the platform-frame, springs, and shaft-frame pivoted to the axle, of springs interposed between the frames, and adjustable connections between the ends of said springs and the platform-frame, substantially as set forth.

3. In a two-wheeled vehicle, the combination of side bars rigidly secured upon the axle, semi-elliptic side springs connecting the cross-bars and adapted to support the body, and shafts or pole pivotally connected to the axle and secured to the front end of the frame by longitudinal springs, substantially as specified.

4. In a two-wheeled vehicle, the combination of a platform-frame connected to the crank-axle, a spring-platform supported by the said frame, adapted to carry the body, and shaft or pole frame, connected to the axle and to the front end of the frame by elastic connections, substantially as specified.

5. In a two-wheeled vehicle, the combination of a platform-frame secured upon the axle, a spring-platform, and shaft-frame supported upon flexion-springs extending from the axle to the front end of the platform-frame, substantially as specified.

6. In a two-wheeled vehicle, the combination, with the platform-frame secured to the axle, of an extension or projection beyond the sides of the platform, and shafts secured to the said extension and having their rear ends pivotally connected to the axle, substantially as specified.

7. In a two-wheeled vehicle, the combination of a platform-frame connected to the axle, and a phæton or drop-front body having its elevated rear portion carried by a spring-support mounted upon the rear end of the frame, and the drop-front of the body carried upon a spring or springs suspended from the side bars, substantially as specified.

8. In two-wheeled vehicles, an adjusting device composed of the vertical bolt K, the top end of which is adapted to a pivotal connection, plate N, in two sections connected by the hinge-joint N', and set-nuts *m o*, substantially as and for the purpose set forth.

In testimony whereof I have signed my name to this specification in the presence of two subscribing witnesses.

CYRUS W. SALADEE.
